UNITED STATES PATENT OFFICE

142,546

DESIGN FOR A PORTABLE VISE

George T. Cumming, Kansas City, Mo.

Application January 8, 1945, Serial No. 117,335

Term of patent 7 years

(Cl. D54—13)

To all whom it may concern:

Be it known that I, George T. Cumming, a citizen of the United States, residing at Kansas City, in the county of Jackson and State of Missouri, have invented a new, original, and ornamental Design for a Portable Vise, of which the following is a specification, reference being had to the accompanying drawing, forming a part thereof.

Fig. 1 is a top plan view of the portable vise, showing my new design.

Fig. 2 is an edge elevational view thereof;
Fig. 3 is an elevational view of one side thereof;
and

Fig. 4 is an elevational view of the opposite side thereof.

I claim:

The ornamental design for a portable vise, as shown.

GEORGE T. CUMMING.
